UNITED STATES PATENT OFFICE.

ANDREW J. NEAFIE, OF BOONTON, NEW JERSEY.

ANTICREEPING DEVICE FOR RAILS.

1,185,234.

Specification of Letters Patent.

Patented May 30, 1916.

Application filed September 1, 1915. Serial No. 48,438.

To all whom it may concern:

Be it known that I, ANDREW J. NEAFIE, a citizen of the United States, and resident of Boonton, county of Morris, State of New Jersey, have invented a certain new and useful Improvement in Anticreeping Devices for Rails, of which the following is a specification.

My invention relates to anti-creeping devices and more particularly to such devices as are used for checking the creeping tendency of railroad rails.

The purpose of my invention is to provide an anti-creeping device which is simple in construction and of a maximum efficiency and in which the parts may be readily combined with each other and with the rail in such a manner as to prevent accidental and unintentional separation thereof without interfering with the automatic adjustment of said parts relatively to each other and to the rail whereby any creeping tendency of said rail is arrested.

A further object of my invention is to provide a means whereby my improved anti-creeping device may be efficiently used with rails of varying weights or sizes.

Other objects of my improvement will appear from the description hereinafter and the features of novelty will be pointed out in the appended claims.

In the accompanying drawings which illustrate a number of examples of my improvement Figure 1 is a side elevation; Fig. 2 is an inverted plan view of the wedge forming part of my construction; Fig. 3 is a cross-section on the line 3—3 of Fig. 1; Figs. 4 and 5 are views similar to Fig. 1 showing slightly different arrangements; Fig. 6 is a side elevation of an adjusting wedge forming part of my invention; Fig. 7 is an inverted plan view thereof; Fig. 8 is a section similar to Fig. 3 showing the adjusting wedge in use and Fig. 9 is a cross-section 45 also similar to Fig. 3 illustrating another arrangement.

As shown in Figs. 1, 2 and 3 the device comprises a clamp 10 which may be of any suitable construction and which in the illustrated example fits over or embraces the base 11 of the rail 12 and is spaced from the lower surface thereof as shown in Fig. 3. The device further includes a wedge 13 adapted to extend between the lower surface

of the rail base 11 and the clamp 10 and 55 having a wedging surface 14 inclining downwardly toward one end of said wedge. As shown in the drawings this wedging surface 14 which may be formed by curving the wedge outwardly, in the assembled condition 60 of the parts preferably fits into a recess 10^a formed for instance at approximately the center of the clamp 10. With this construction relative movement between the clamp 10 and the wedge 13 in a direction transverse to the rail 10 is prevented and a 65 lengthwise extending recess 13^a is formed in the upper surface of said wedge 13. It will of course be understood that this arrangement is not arbitrary and that the same may 70 be changed if desired. The butt or large end of the wedge 13 is further continued and bent to form a head or the like 15 adapted, in the operative position of the parts, to bear against a tie 15^a or other stationary part of the track or road bed for the purpose to be more fully set forth hereinafter. In addition to this the opposite or 75 small end of the wedge 13 is continued to form a curved or otherwise shaped end 80 member 16, the latter itself being continued to form an arm 17 located beneath and spaced from the wedge 13, the said arm extending toward the head 15 and preferably terminating at a distance therefrom as 85 clearly shown in Fig. 1. The inner or upper surface of this arm 17 in the form now being described is provided with a plurality of corrugations or the like 18 which may be formed in any suitable manner, for 90 instance as shown in Fig. 1, it being of course understood that the corrugations or the like are necessary only on the inner or upper surface of said arm 17. These corrugations 18 are adapted to receive or accommodate a projection 19 extending downwardly from the clamp 10 preferably at approximately its central portion as shown in Fig. 3. This projection 19 may be of any suitable shape and is adapted in combination 95 with the corrugations 14 or the like to prevent separation of the parts as will appear more fully hereinafter. In placing the parts of this form of my improvement in operative position the clamp 10 is first passed through 100 the loop formed by the curved end member 16 and its opposite ends placed over the rail base 11 which brings the wedge 13 between

the clamp 10 and the lower surface of said base 11. The parts are so positioned on the rail 12 as to bring the head 15 into engagement with the tie 16 or other stationary portion of the track or road bed it being understood that the wedge points in the direction opposite to that in which the rail tends to creep. The clamp 10 is now moved toward the head 15 with the wedging surface 14 located in the depression or recess 10^a and forced home on said wedge whereby through the medium of said wedging surface 14 in coöperation with the clamp itself the latter is caused to firmly and securely grip the rail base 11 at opposite edges. Owing to the fact that the normal distance between the wedge and the inner or upper surface of the arm 17 is less than the distance between the free end *a* of the projection 19 and the surface *b* of the clamp 10, the arm 17 will be depressed as the clamp 10 is forced home on the wedge. The depression of the said arm 17 is possible owing to the fact that the end member 16 gives the same a certain amount of resiliency or in other words permits it to yield as will be clearly apparent. As the movement of the clamp 10 relatively to the wedge 13 is continued in the operation of properly combining the parts, the said projection 19 will snap into the first corrugation 18 and if a further adjustment is necessary will move out of same and snap into the next corrugation as the movement is continued, this operation being repeated until finally the parts are properly adjusted with said projection 19 seated in one of said corrugations 18. In any case the clamp 10 will be firmly locked against a return movement thus normally preventing a separation of the wedge and clamp and yet permitting the latter to move farther along on the wedge 13 toward the head 15 under the creeping tendency of the rail. It will be understood that when the rail tends to creep it carries the clamp 10 with it and thus forces it lengthwise of the wedge 13 which is held against movement in the creeping direction of the rail by the tie or other stationary portion of the track or road bed. In this manner the clamp 10 will be caused to still more firmly grip the rail base whereby the creeping of said rail is efficiently and quickly arrested. During these operations the projection 19 will pass from one corrugation 18 to the other so that an unintentional separation of the wedge and clamp is at all times effectively prevented.

The arrangement illustrated in Fig. 4, generally speaking, is the same as in Figs. 1-3 with the exception that the corrugations 18 are replaced by a series of teeth 18^a. These teeth 18^a may simply appear on the upper or inner surface of the arm 17 or said teeth 18^a may be formed by shaping the said arm for instance as shown in Fig. 4. With

the arrangement at present being described the projection 19^a on the clamp 10 is shaped to fit the teeth 18^a snugly as is also clearly illustrated in Fig. 4. The application and operation of this construction is exactly the same as in the form first described and the same advantages are present therein. It will of course be understood that the shape of the teeth 18^a and of the projection 19^a may be varied as desired.

In Fig. 5 the arm 17 is formed with inclined portions 17^a and 17^b whereby a single projection 18^b is produced behind which the clamp 10 is arranged to set when the parts are fully assembled. The operation of this form, which will be clear from the illustration, is substantially the same as in the two previous forms, it being understood that the resiliency of the arm 17^a is sufficient to prevent a return movement of the clamp beyond the projection 18^b regardless of what part of the portion 17^a is in engagement with said clamp 10.

It will be seen, with all the illustrated forms of my improvement so far described, that the clamp is movable relatively to the wedge in one direction to cause the device to efficiently arrest any creeping of the rail but is normally incapable of being separated therefrom by any movement in the opposite direction. The latter movement of the clamp will in the operative condition of the parts always be arrested before said movement is sufficient to disarrange the parts or to render the clamp sufficiently loose on the rail base to permit the rail to move relatively to said clamp or to slide therethrough as the creeping tendency is exerted.

To intentionally separate the clamp from the wedge when for any reason this is desired it is merely necessary to force the various arms against their tension a sufficient distance to disengage the various projections or clamps from the corrugations, teeth or projections and thus permit the clamp to be freely moved toward the small end of said wedge. This actuation of the arms may be readily accomplished by means of a crow-bar or other suitable implement. It will of course be understood that in some cases the forms shown in Figs. 1 and 4 may include merely a single corrugation or tooth properly positioned to secure the intended results and also that the form shown in Fig. 5 may be provided with more than one projection if desired or found advantageous. With my improvement so far referred to the parts of the device are firmly locked against disarrangement from vibration, contraction or other causes and are at all times secured against unintentional separation thus assuring a maximum of efficiency under all conditions.

As is well known, railroad rails are made of different weights and with bases of dif-

ferent thicknesses so that ordinarily a device of the present character intended for use with a heavy rail having a thick base could not be satisfactorily used with a lighter rail having a thinner base and special devices would have to be constructed for each different type of rail. To overcome the necessity for this I have provided a means whereby my improvement may be efficiently used with rails of any weight or thickness of base. As shown in Figs. 6, 7 and 8 this means comprises an auxiliary or adjusting wedge 13^b having a head 15^b and shaped to form a surface 14^a adapted to fit into the recess 10^a of the main wedge 13. When it is desired to use a device intended for a heavy rail in combination with a rail of lighter weight, this adjusting wedge 13^b is simply combined with the main wedge 13 to increase the thickness thereof as shown in Fig. 8. In the combined condition the adjusting wedge 13^b is superimposed on the main wedge 13 with the surface 14^a in the recess 10^a and the head 15^b against the head 15. In this manner the wedging means is increased in thickness sufficiently to compensate for the relatively larger space between the rail base of a lighter rail and the clamp normally intended for use with a heavier rail so that the device operates equally well with both rails. By providing a series of auxiliary or adjusting wedges of different dimensions as to thickness, the device may be efficiently used with rails of any weight. The coöperation of the surface 14^a and recess 10^a prevents separation of the main and auxiliary wedges in a transverse direction, it being understood that in some cases both the recess 10^a and the surface 14^a or the latter alone may be omitted, it being obvious that the wedging surface 14 on the wedge 13 may be constructed or produced otherwise than as shown.

Instead of using an auxiliary or adjusting wedge for the purpose described I may construct the clamp 10 with a relatively straight portion 10^b and an upwardly inclined continuing portion 10^c and provide recesses 10^d and 10^e located respectively in the straight portion 10^b and the inclined portion 10^c. With this arrangement it will be seen that the recess 10^e is in a different plane than the recess 10^d and is so located as to equalize the distance between itself and the base of a light rail with the distance between the recess 10^d and the base of a heavier rail. Thus by inserting the wedging surface 14 into the recess 10^d or 10^e as the case may be the same device may be used equally well with light or heavy rails. It will of course be understood that a series of recesses 10^e may be provided in the inclined portion 10^c to still further increase the range of usefulness of the device.

65 Various other changes in the arrange-

ments shown and described may be made within the scope of the claims without departing from the spirit of my invention.

I claim:

1. An anti-creeping device for rails comprising a clamp arranged to engage the rail-base, a wedge located between said rail-base and clamp whereby the latter is caused to grip said rail-base and arrest the creeping tendency of the rail and a resilient means depending from the reduced end of said wedge and extending back toward the enlarged end thereof, said means being arranged to engage said clamp whereby separation of said clamp and wedge is normally prevented. 70

2. An anti-creeping device for rails comprising a clamp arranged to engage the rail-base, a wedge located between said rail-base and clamp whereby the latter is caused to grip said rail-base and arrest the creeping tendency of the rail, a resilient arm connected with the small end of said wedge and extending back toward the enlarged end thereof and a projection on said arm arranged to snap behind said clamp whereby separation of said clamp and wedge is normally prevented. 85

3. An anti-creeping device for rails comprising a clamp arranged to engage the rail-base, a wedge located between said rail-base and clamp whereby the latter is caused to grip said rail-base and arrest the creeping tendency of the rail, an arm spaced from said wedge, a connection from the small end 90 of said wedge to one end of said arm, the opposite end of the latter being free, and a plurality of projections on said arm adapted to successively engage said clamp whereby separation of said clamp and wedge is 105 normally prevented.

4. An anti-creeping device for rails comprising a clamp engaging the rail-base and movable therewith in the direction of creep, a wedge for resisting the movement of 110 said clamp whereby the creeping tendency of the rail is arrested, means whereby said wedge is held against movement in the creeping direction and means connected with the small end of said wedge and extending back toward the wedge holding means whereby a movement of the clamp tending to separate it from the wedge is arrested. 115

5. An anti-creeping device for rails comprising a clamp arranged to engage the rail-base, a wedge located between said rail-base and clamp whereby the latter is caused to grip the rail-base and arrest the creeping tendency of the rail, a head extending from 120 the butt end of the wedge and arranged to engage a stationary element to secure said wedge against movement in the creeping direction, an arm spaced from said wedge and extending toward the said head, a con- 125

nection from one end of said arm to said small end of said wedge and means on said arm adapted to secure said clamp against a movement tending to separate it from said wedge.

6. An anti-creeping device for rails comprising a clamp arranged to engage the rail-base, a wedge located between said rail-base and clamp whereby the latter is caused to grip said rail-base and arrest the creeping tendency of the rail, a resilient arm connected with said wedge, and coöoperating projections on said arm and clamp whereby separation of said clamp and wedge is normally prevented.

7. An anti-creeping device for rails comprising a clamp arranged to engage the rail-base, a wedge located between said rail-base and clamp whereby the latter is caused to grip said rail-base and arrest the creeping

tendency of the rail and an adjusting wedge arranged to be inserted between said first wedge and said rail base whereby said clamp and first wedge are adapted to be operatively combined with rail-bases of different dimensions. 25

8. An anti-creeping device for rails comprising a clamp arranged to engage the rail-base, and a wedge arranged to extend between said clamp and wedge to arrest the creeping tendency of the rail, said clamp being provided with a plurality of recesses located in different planes for the accommodation of said wedge whereby said clamp and wedge are adapted to be operatively combined with rail-bases of different dimensions. 30 35

In testimony whereof I have hereunto set my hand.

ANDREW J. NEAFIE.
